(57) **CLAIM**

The ornamental design for an electric self balancing scooter, as shown and described.

DESCRIPTION

The patent or application file contains at least one drawing executed in color. Copies of this patent or patent application publication with color drawing(s) will be provided by the Office upon request and payment of the necessary fee.

1. Electric self balancing scooter

2. Electric self balancing scooter

1.1 : Front

1.2 : Back

1.3 : Left

1.4 : Right

1.5 : Top

1.6 : Bottom

1.7 : Perspective

2.1 : Front

2.2 : Back

2.3 : Left

2.4 : Right

2.5 : Top

2.6 : Bottom

2.7 : Perspective

The elements shaded in a transparent red wash are included for the purpose of illustrating portions of the scooter head and form no part of the claimed design.
